UNITED STATES PATENT OFFICE.

ANTONINO MÓNACO, OF BUENOS AIRES, ARGENTINA.

SUSPENDERS.

1,414,199.

Specification of Letters Patent. Patented Apr. 25, 1922.

Application filed September 3, 1919. Serial No. 321,462.

(GRANTED UNDER THE PROVISIONS OF THE ACT OF MARCH 3, 1921, 41 STAT. L., 1313.)

To all whom it may concern:

Be it known that I, ANTONINO MÓNACO, subject of the King of Italy, residing at Buenos Aires, Argentine Republic, have invented certain new and useful Improvements in Suspenders, for which I have filed an application in Argentina, application #18,314, filed July 29, 1918, and in Brazil, application #15,282, filed October 3, 10 1918, of which the following is a specification.

The present invention refers to certain improvements in suspenders and has essentially for object the provision upon the said 15 articles of attire, and at any point of the same, of pockets of any kind.

In order that the invention may be clearly understood and easily put into practice, it has been represented in the attached drawing, in which:—

The figure is a view in perspective of the form of suspenders in accordance with the present invention.

With reference now to the figure, *a* is 25 a pair of suspenders of the usual type in which the straps which are usually secured to the front portion of the trousers have been omitted. These suspenders are provided with a common buckle 1 on each strap, 30 by means of which is affixed to the extremity of the same a strip of leather or similar stout material 2 forming a loop upon which is sewn or attached in any suitable manner the back 3 of a pocket *b*. 4 is the lower portion of the said back, which is cut slanting

in order to fit the usual position of the trousers waist band, and in which are two button-holes 5, 5 which serve to secure the extremity of the pocket to the ordinary buttons of the trouser waist band. 6 is the front of the pocket, preferably of flexible or elastic material and having at the top an elastic band 7 with the object of keeping the mouth closed, a cover 8 also being provided, which cover is attached to the back 3 and 45 is provided with a button-hole 10 which permits of its being secured to the button 9 on the front 6 of the pocket.

I claim as my invention:

The combination, with a pair of suspenders comprising connected shoulder straps; of a pocket for each of said straps, comprising front and back members, said pocket having a slanting lower edge to conformably fit against a trouser waist band; a 50 cover attached to the back member; means on the front member of the pocket for holding the cover in a closed position; and a band for each strap forming a loop secured to the back member of the pocket and provided with a buckle for connection to the lower end of said shoulder straps, each pocket being provided at its lower corners with button holes to removably attach the corresponding strap to the trouser waist 55 band and constituting the immediate connection between the strap and the trouser waist band.

In testimony whereof I affix my signature.
ANTONINO MÓNACO.
